UNITED STATES PATENT OFFICE.

FLOYD F. RORABECK, OF AZUSA, CALIFORNIA.

LOCK.

1,374,393.

Specification of Letters Patent. Patented Apr. 12, 1921.

Application filed March 7, 1918. Serial No. 221,081.

To all whom it may concern:

Be it known that I, FLOYD F. RORABECK, a citizen of the United States, residing at Azusa, in the county of Los Angeles and 5 State of California, have invented a new and useful Improvement in Locks, of which the following is a specification.

My invention relates to locks and lock mechanisms adapted to be mortised or otherwise secured in a door, and comprising a latch and a bolt, the latch being operated by the handle of the door and the bolt being operated by a key. This is what may be regarded as the standard form of lock for 15 dwelling construction and must be of such a size and shape as to be readily secured within the body of an ordinary wood door.

In the commercial forms of such locks it is common practice for the mechanism of 20 the lock to be placed in a rectangular metal box which is somewhat thinner than the door and which is placed in a rectangular mortise cut in the door from the edge thereof. The cutting of these mortises is a difficult 25 and tedious matter and one that can only be entrusted to a skilled workman.

The principal object of my invention is to provide a lock in which the mechanism is contained in two cylinders which may be 30 inserted in round holes bored with an auger in the edge of the door. By using such round holes it is possible to place the lock without using the chisel except in a very limited extent in cutting a shallow mortise 35 for the face plates. I am aware that previous inventors have attempted to use locks in which the mechanism is contained in cylindrical members which are placed in auger holes, but so far as I am aware none of the 40 previous locks have been a success for the reason that the two cylinders have been secured in substantially parallel relationship with each other, thus necessitating the boring of the two auger holes in practically parallel 45 relationship which is a very hard thing to do even for a skilled workman.

It is a further object of my invention to provide a lock in which the mechanism is inclosed in two cylinders suitable in size to 50 be placed in auger holes bored in a door, and which is so constructed that these auger holes can vary widely from parallelism without making it difficult or impossible to place the lock.

55 In using locks commercially, it is necessary to provide a latch which can be set to

catch from either side. It is common practice to make these latches with an inclined face which slips easily over the latch plate and forces the latch into the door as the 60 door is closing, but which hooks into an opening in a latch plate fixed in the door frame when the door is closed, the latch then being retracted when it is desired to open the door by turning the handle of the 65 door. In practice, due to the fact that doors may swing either way, it is necessary that the inclined face of the latch be so arranged that it can be presented to either side. In many locks it is necessary for the carpenter 70 who is placing the lock to take the lock apart and reverse the latch to suit the direction the door swings. This is very objectionable as it takes time and the parts of the lock are not always easy to handle so that they fall 75 out and become lost or are put together in a faulty manner.

It is a further object of my invention to provide a latch mechanism which may be inserted in a door either right or left hand 80 without disturbing the interior of the mechanism.

Further objects and advantages will be made evident hereinafter, or to one skilled in handling locks, will be evident from a 85 perusal of the following description and an examination of the drawing.

The invention consists of the novel arrangement and combination of parts as set forth hereinafter.

In the drawings, which are for illustrative purposes only, and which show one form of lock only in which my invention may be embodied,

Figure 1 is a view of a door equipped with 95 a lock embodying my invention, and it will be observed that so far as the external appearance is concerned, the lock looks exactly like many forms of standard locks in common use.

Fig. 2 is a perspective view of the lock itself, the door being shown in dotted lines and the handles, handle plates, etc., being omitted for the sake of better illustrating the invention.

Fig. 3 is an elevation of the lock, partly in section, through the center of the door.

Fig. 4 is a section on a plane represented by the line 4-4 of Fig. 3.

In the form of my invention illustrated 110 in these drawings, the door 11 is a wooden door of standard construction. The lock

consists of a latch mechanism 12 having a latch 13 and a bolt mechanism 14 having a bolt 15. The latch is operated as will later be explained by the square shank 16 of the handles 17 and the bolt is operated by a key 18. Ornamental handle plates 19 may be used on either side of the door through which the key may be inserted through a keyhole 20.

- 10 The latch mechanism comprises a round tube 21 of small enough diameter to go in an auger hole which may be readily bored in the door 11. The forward end of the tube 21 is rigidly secured to a latch plate 22. 15 This latch plate has a square hole through which the latch 13 may project and has two screw holes 23. The plate 22 is symmetrical about the center line of the latch mechanism 12 and the tube 21 in both a plane passing 20 through the center of the door and a plane at right angles thereto passing through the axis of the tube 21. The screw holes 23 are also symmetrically located with regard to that axis. As a result the tube 21 may be 25 inserted in the door as shown, or it may be reversed so that the inclined face of the latch will be on the opposite side of the door, thus allowing the door to swing either way and allowing the carpenter to place the 30 latch mechanism 12 in the door either way without disturbing the interior of that mechanism.

The bolt mechanism 14 is placed in a tube 31 which in turn is secured rigidly to a bolt 35 plate 32 which need not be symmetrical and which I find convenient to equip with only one screw hole 33.

The plates 22 and 32 are set into a shallow mortise in the edge of the door and each is 40 allowed to find its own bearing independent of the other. If the two auger holes are bored very much out of line, the tubes 21 and 31 will nevertheless slip readily in place as they have no common connection that 45 necessitates their being parallel. After the mechanisms 12 and 14 are put in place a lock plate 41 is placed over the plates 31 and 21 so that any angularity or irregularity in their location is covered. By making the 50 two mechanisms 12 and 14 independent and independently securing them in the door I am able to place them without using skilled labor, and without using any great pains as to the distance apart between the auger holes 55 or as to getting these holes parallel. I believe that previous attempts to use cylinder locks have failed for lack of this very essential feature.

The type of mechanism used in the tubes 60 12 and 14 is more or less immaterial to the above advantages. I have, however, shown practical and satisfactory forms of latch and

bolt mechanisms in the drawing in which 61 is a latch body on which the latch 13 is formed, this body having a central opening 62 through which the shank 16 passes. A cam 63 is rigidly secured on the shank 16 and is so formed that it engages two projections 64 formed on the body 61. A compression spring 65 presses against the end 70 of the body 61 and against the closed end of the tube 21, thus tending to hold the body 61 and the latch 13 in their extreme lefthand positions, as viewed in Fig. 3. As the handle 17 is turned the cam 63 is also turned 75 and the latch 13 is retracted.

The bolt mechanism 14 comprises a bolt body 71 having tumbler notches 72 formed in its upper surface and having a central guard opening 73 of the form shown in Fig. 3. 80 Abutments 74 are formed on either side of the openings 73. Tumblers 75, carried on springs 76, are located at either side of the body 71 and the springs 76 are rigidly fixed in the tube 31. When the key 18 is inserted 85 it will be stopped by the body 71 unless it is of the proper size and shape to pass through the opening 73. If so, it will, on being turned, first lift the tumblers out of their notches and then, by contacting with 90 the abutments 74, will throw the bolt from open to closed position or vice versa.

What I claim is:—

1. A lock comprising a latch mechanism, a bolt mechanism, each of said mechanisms 95 being mounted inside a cylindrical tube of proper size to slip readily inside a standard wooden door, a flat latch plate rigidly secured to the tube which carries the latch mechanism, a flat bolt plate rigidly secured 100 to the tube which carries the bolt mechanism, and a lock plate fitting in the same mortise as said latch and said bolt plate completely hiding and covering said plates.

2. A lock comprising a latch mechanism, 105 a bolt mechanism, each of said mechanisms being mounted within a cylindrical tube of proper size to slip readily inside a standard wooden door, a securing plate on the latch mechanism seated in a mortise in the door, 110 a plate secured to the bolt mechanism seated in the same mortise, a lock plate fitting over said bolt plate and latch plate in the same mortise, and fastening means consisting of screws on said lock plate extending through 115 the latch plate and bolt plate into the door, said plate secured to the bolt mechanism being a separate plate from the securing plate on the latch mechanism.

In testimony whereof, I have hereunto set 120 my hand at Los Angeles, California, this 1st day of March, 1918.

FLOYD F. RORABECK.
